UNITED STATES PATENT OFFICE.

JOHN KYLE, OF SPRINGFIELD, OHIO, ASSIGNOR TO MIEHLE PRINTING PRESS & MANUFACTURING COMPANY, OF CHICAGO, ILLINOIS, A CORPORATION OF ILLINOIS.

ADJUSTABLE GRIPPER-PAD.

1,271,329.

Specification of Letters Patent.

Patented July 2, 1918.

Application filed April 14, 1916. Serial No. 91,020.

To all whom it may concern:

Be it known that I, JOHN KYLE, a citizen of the United States, residing at Springfield, in the county of Clark and State of 5 Ohio, have invented certain new and useful Improvements in Adjustable Gripper-Pads, of which the following is a specification.

The object of the invention is the provision of improved gripper pads for printing 10 presses, and means for leveling and clamping in position the gripper pads, whereby to uniformly raise or lower the same in order to adapt them to varying thickness of paper.

15 In order that the invention may be readily understood, a preferred embodiment of the same is set forth in the accompanying drawing and in the description based thereon. As, however, the invention is susceptible 20 of embodiment in other and varied constructional forms without departure from the essence thereof, the drawing and description are to be taken in an illustrative and not in an unnecessarily limiting sense. In 25 the drawing—

Figure 1 is a fragmentary cross sectional view through a portion of the printing cylinder showing in side elevation the arrangement of the grippers, the gripper pads and 30 the blanket clamping device;

Fig. 2 is a face view of the combined blanket clamp and gripper pad support;

Fig. 3 is a rear view of Fig. 2; and

Fig. 4 is a longitudinal section through 35 the device showing the gripper pad adjustment;

Fig. 5 is a perspective view of the plunger upon which the gripper pad rests; and

Fig. 6 is a similar view of the gripper 40 pad block itself.

In the drawings the cylinder is indicated at 11 mounted in the usual manner in the side frame of the press and cut away at 12 to provide for the mounting of the various 45 devices by means of which the blanket or plate is clamped in position and the gripper pads are held in proper adjustable position for coöperation with the grippers themselves.

50 As illustrated, upon the side wall of the cutaway portion 12 of the cylinder is disposed a bracket 13 serving as a support for a shaft 14, the angular position of which is controlled by means of the arm 15 and the 55 set screw 16. Upon this shaft at proper

intervals are mounted the supports 17 for the blanket clamp 18 and the gripper pad 19, these supports being held in adjusted position by means of the clamping screw 20 as will be readily understood. The shaft 60 21 serves as a support for the grippers 22 mounted in the usual manner to coöperate with the gripper pads 19, which latter are cubical blocks of wood or other non-metallic substance.

65 The head of the gripper pad support 17 has formed therein a recess, here shown as being square in cross section, which recess accommodates a plunger plate 23 having a stem 24 extending through a bore of the support into a transverse chamber 25. Upon the plunger plate 23 rests the block 19 forming the gripper pad. The lower end of the stem 24 is preferably beveled as indicated at 26 to correspond to the coned surface 27 70 of an adjusting screw 28 the head and coned portion of which is accommodated within the chamber 25 while the end thereof has threaded engagement with the support at 29. The head of the gripper pad support is 75 slit to render the same expansible and contractible within a limited extent and is provided with ears 30, 30 traversed by the clamping screw 31, whereby the head may be clamped upon the inserted and adjusted 80 gripper pad 19.

85 It will be readily apparent that by turning the screw head 28 to adjust the position of the same within the chamber 25 by means of the threaded connection 29 the screw will 90 be advanced or retracted and the plunger plate 23 raised or lowered by means of the engagement of the stem 24 with the cone face 27 of the screw, thus raising and lowering the gripper pad 19 toward or from the periphery of the cylinder in a substantially 95 radial direction. The radial adjustment of the gripper pad having been effected, the clamping screw 31 is turned to contract the walls of the recess upon the gripper pad 100 whereby the same will be permanently held in that position until readjustment is required.

105 The adjustment of the gripper pads individually may be combined with a simultaneous and uniform adjustment of the gripper pad support throughout the length of the cylinder in any approved manner, if desired.

It has heretofore been usual to employ me- 110

tallic gripper pads. I have found that pads of material other than metal, such as wood, afford a better pad surface between which and the grippers themselves to grip the sheet. By making these non-metallic pads in the form of cubical blocks seated in a rectangular recess, the pads may be turned over from time to time as the surface may become irregularly worn to present a fresh operative surface.

I claim:

1. The combination with a printing press cylinder, and the grippers, of gripper pad supports provided with equilateral polygonal recesses and correspondingly shaped non-metallic gripper pads seated in said recesses, whereby the pads may be turned to expose any side at will for coöperation with the grippers.
2. The combination with a printing press cylinder, and the grippers, of gripper pad supports provided with equilateral cubical recesses, and cubical wooden gripper pads seated in said recesses, whereby the pads may be turned to expose any side at will for coöperation with the grippers.
3. The combination with a printing press cylinder, and the grippers, of gripper pad supports, gripper pads guided for movement relative to the supports, a coned adjusting member rotatably mounted in the supports and arranged to act upon the pad whereby

the rotation of the adjusting member will raise and lower the pad, and means to clamp the pad in adjusted position relative to the 35

40 support.

4. The combination with a printing press cylinder, and the grippers, of gripper pad supports provided with rectangular recesses, cubical wooden gripper pads seated in said recesses, a coned adjusting member rotatably mounted in the supports and bearing upon the pad and upon the cone whereby the rotation of the adjusting member will raise and lower the pad.

45

5. The combination with a printing press cylinder, and the grippers, of gripper pad supports provided with rectangular recesses, cubical wooden gripper pads seated in said recesses, a coned screw transversely threaded 50 in the support below the pad, a plunger bearing upon the pad and upon the cone, whereby the rotation of the screw will raise and lower the pad, and means to clamp the walls of the support upon the pad to maintain the latter in adjusted position.

55

In testimony whereof I have hereunto signed my name in the presence of two subscribing witnesses:

JOHN KYLE.
